Cecil C. Fischer
ATTORNEY

UNITED STATES PATENT OFFICE.

HENRY D. TUCKER, OF AVENEL, NEW JERSEY.

CHILD'S SAND-BOX FOR PLAY PURPOSES.

1,389,020.

Specification of Letters Patent. Patented Aug. 30, 1921.

Application filed December 3, 1919. Serial No. 342,060.

To all whom it may concern:

Be it known that I, HENRY D. TUCKER, a citizen of the United States, residing in the town of Avenel, county of Middlesex, and State of New Jersey, have invented certain new and useful Improvements in Children's Sand-Boxes for Play Purposes, of which the following is a full, clear, and exact description, such as will enable others skilled in the art to which it pertains to make, construct, and use the same, reference being had to the accompanying drawings, and to numerals of reference marked thereon, forming a part of this specification.

The invention relates to children's sand boxes for play purposes, and has in view a knock-down construction embodying simplicity and strength, and which may be easily erected and disassembled, and when in the latter form, closely packed for shipment or storage.

To this end the invention consists of a box having a bottom, side walls, end walls and corner posts. Each post is so constructed that one face thereof is secured to the end wall and the other face of each post secured to the side walls and bottom, and bolts or other equivalent devices securing the bottom and walls together.

The invention further contemplates the provision of a sliding seat adapted to engage with the side walls of the box, said seat being provided with collapsible means whereby the sand in the box can be leveled by simply sliding the seat along on the top of the side walls.

Reference is to be had to the accompanying drawings, forming a part of this specification, in which similar characters of reference indicate corresponding parts in all of the views.

Figure 1 represents, a perspective view of the preferred form of my invention.

Fig. 2 represents, a perspective view of the sliding seat designed to have sliding engagement with the top of the side walls of the box, as clearly indicated in dotted lines in Fig. 1 of the drawings.

Fig. 3 represents, a transverse section taken on lines $x-x$ of Fig. 2.

Fig. 4 represents, a perspective view of the box partly disassembled, with one side wall and one end wall removed.

Figs. 5 and 6 represent side and front elevations of one of the corner posts; and

Fig. 7 represents, the box assembled, closely packed for shipment or storage.

The box body is primarily made up of a bottom 1, preferably consisting of a plurality of tongued and grooved boards, side walls 2, end walls 3, and corner posts 4. Secured to the under side of the bottom, preferably three in number, are the cleats or braces 5, one arranged near each end of the bottom, and one midway of its length thereof, as clearly indicated in Figs. 4 and 7 of the drawings.

The outer boards of the bottom 1 at the corners thereof are recessed as at 6, and the ends of the end cleats or braces 5 slightly overlap the recessed portion 6. The longitudinal edges of the end cleats 5, are located a short distance inward from the ends of the bottom 1 as clearly indicated in Figs. 4 and 7 of the drawings.

The corner posts 4 are on two sides thereof, provided with grooves 7 and 8, which extend across two of the adjacent faces thereof. The upper portions of the posts are provided with holes 9 corresponding with holes 10 in the side walls 2 for the reception of bolts 11, which are provided with wing nuts 12 and by means of which the box is rigidly secured together.

In practice the posts 4 are secured to the end walls 3 as clearly indicated in Fig. 4 of the drawings, in any desired or convenient manner, and when it is desired to assemble the box the posts 4 are received into the recessed portion 6 of the bottom 1 with the groove 7 engaging with and receiving the end of the outermost board of the bottom 1, and the groove 8 engaging with and receiving the end of the cleat 5 which as previously stated slightly overlaps the recessed portion of the bottom and which is clearly illustrated in Figs. 1 and 4 of the drawings. In this manner the bottom 1 together with the ends of the end cleats 5 are securely interlocked with the corner posts 4. The two side walls 2 are then placed into position against the outer faces of the corner posts with their ends fitting in between the ends of the side walls 3.

In Figs. 2 and 3 of the drawings, a seat 14 is illustrated, the under side of which is provided with cleats 15 whereby the seat is positioned to slide along the top of the side walls 2. Hingedly connected to the under side of the seat 14 is a scraper or leveler 17, which

when in the position indicated in Figs. 2 and 3 of the drawings is utilized to level the sand in the box when it is desired to use the sand for drawing of figures or the like.

5 This scraper 17 when not in use can be moved in the direction indicated by the arrow in Fig. 3 of the drawings, so that it will lie flat on the under side of the seat 14.

In Fig. 7 the device is shown assembled, 10 closely packed for shipment or storage in which case the end walls 3 together with their attached legs 4, are laid flat against the under side of the bottom 1 and the side walls 2 are laid on top of the end walls 3, 15 the holes 10 in the side walls being utilized for the reception of ordinary wood screws 18 which are screwed into the cleats 5. In this manner the device can be readily stored away when not in use, or packed for 20 shipment.

It will thus be seen that I have produced a sand box for childrens' play purposes, of 25 a knock-down construction embodying simplicity and strength, one which may be easily erected and disassembled, and when in the latter form, may be closely packed for shipment or storage.

I am not aware that devices of this kind have heretofore been produced in the knock-down form and for that reason desire to 30 claim the device as broadly as the art will permit.

It has been customary, to my knowledge, whenever a sand box for play purposes was 35 desired the same was built to order at considerable cost, and which was permanently put together, without any of the knock-

down features for storage or shipment purposes.

While the device described is the preferred embodiment of my present invention, I do not care to restrict myself to the exact details of construction, combination and arrangement herein set forth, it being obvious that minor variations thereof, not involving the exercise of invention, may be made by any skilled mechanic, and such departures from what is herein described and claimed not involving invention, I consider as within the scope and terms of my claims. 45 I claim.

1. A knock-down sand box for play purposes having a bottom provided with end cleats and recessed corners, side and end walls, posts provided with grooves to fit into 55 the recessed corners, the bottom and cleats to be received by said grooves and means passing through the posts and walls for binding the parts together.

2. A knock-down sand box for play purposes having a bottom provided with end cleats, side and end walls, posts constructed to interfit with said bottom and end cleats and means binding the parts together, a seat 60 slidably mounted upon two of the oppositely arranged walls and a scraper hingedly secured to the under side of said seat.

This specification signed and witnessed this first day of December, 1919.

HENRY D. TUCKER.
